UNITED STATES PATENT OFFICE.

JAMES C. RICKETSON, OF MILWAUKEE, WISCONSIN.

SIGNAL FOR ENGINES.

SPECIFICATION forming part of Letters Patent No. 374,322, dated December 6, 1887.

Application filed April 5, 1887. Serial No. 233,816. (No model.)

To all whom it may concern:

Be it known that I, JAMES C. RICKETSON, of Milwaukee, in the county of Milwaukee, and in the State of Wisconsin, have invented certain new and useful Improvements in Signals for Engines; and I do hereby declare that the following is a full, clear, and exact description thereof.

My invention relates to devices for indicating at any point distant from an engine or its shaft the direction in which the latter is revolving, and will be fully described hereinafter, and pointed out in the claims.

In the drawings, Figure 1 is a view of part of a marine engine with one form of my present invention applied thereto. Fig. 2 shows a pneumatic push-button such as I use in the form shown in Fig. 1. Fig. 3 shows an electric push-button which may be used with electrical instead of pneumatic connection with the distant signal.

My invention is in part an improvement on the devices set forth in my patent, No. 356,792, granted me February 1, 1887; and this improvement consists in a simpler arrangement and fewer number of parts and a more direct connection with the actuating push-button, whereby either electric or pneumatic signals may be actuated by the movement of the eccentric-rods of the engine.

As in my patent just named, I have illustrated my device in connection with a marine engine for use on a steamboat; but it is capable of use in connection with any reversible engine.

A A' represent the eccentric-rods of a marine engine, and B is the engine-shaft.

C C' designate brackets projecting from the frame of the engine toward the eccentric-rods, 40 and carrying push-buttons D D', those shown in Fig. 1 being supposed to be pneumatic push-buttons, shown in sectional detail in Fig. 2, where the push-rod d' (or d) has a concave plate, d², formed integral therewith, (or secured thereto,) which bears directly against a rubber bulb, e, connected in turn to the pneumatic tube E' (or E.)

F F' are the bells or other signals or annunciators, a pneumatic bell or annunciator, of course, being used with pneumatic tubes.

Fig. 3 shows an electric push-button of a

form too common to need any description, and which may be used in place of the pneumatic push-button just described, in which event wires e' e² would of course connect with a battery (not shown) and with the bells or other signals F F', (which would be then any ordinary electric signals instead of pneumatic,) in the usual manner. In some instances it might be better to have the eccentric-rods A A' provided with swelled or rounded bosses or projections a and a', as shown in dotted lines, to insure closer contact with the push-rods of the push-buttons, and these bosses may be either cast with the rods A A' or secured to them, as 65 more convenient in any given case; and, if desired, springs may be interposed back of the push-buttons on the brackets C C' to guard against injury or jarring of the device.

The operation of my device is substantially 70 the same as in my before-named patent, except that the push-rod of the push-button is operated upon directly by the eccentric-rod, instead of through the interposition of a series of levers, as heretofore, making a simpler and 75 cheaper device than that shown in said patent and one equally effective.

In the illustration given the eccentric-rod A is supposed to be making the connection, as shown in full lines, and consequently the shaft 80 B is all the time revolving in one direction. In this movement of the shaft the eccentric-rod A is thrown so far to the left as to cause it to press against the adjacent push-button D, and thereby to directly actuate the signal 85 F. In dotted lines the positions of the eccentric-rods are shown when the shaft B is revolved in the opposite direction, when the eccentric-rods are thrown over to the right far enough to cause the eccentric-rod A' to press 90 against the push-button D', and thereby to instantly actuate the signal F'.

As before, I have only shown bells; but of course I may use any form of signal or annunciator in place thereof or in addition thereto. 95 I may use only one such push-button and signal on one side of the engine, or two, as shown, so that the pilot or captain of a vessel, for instance, may know always in which direction the shaft is revolving, either by the ringing 100 or non-ringing of the bell, in one instance, or by noticing which bell is ringing or which sig-

nal operating if push-buttons are applied adjacent to each of the eccentric-rods, as shown.

For convenience, I propose to locate the push-buttons on brackets extending from the engine-frame, as stated; but it will be understood that the said push-buttons may be upon any suitable support—such as a beam or independent frame—provided they are adjacent to the eccentric-rods of the engine, as hereinbefore described.

Having thus fully described my invention, what I claim as new, and desire to secure by Letters Patent, is—

1. The combination of a reversible engine with a distant signal and a push-button connected to said signal and located upon the engine-frame or other suitable support adjacent to one of the eccentric-rods of the engine, whereby the said rod in its movement will

make direct contact with the push-rod of said push-button, and thereby actuate the signal.

2. The combination of a reversible engine with a distant pneumatic signal, a pneumatic push-button located on the frame of the engine or other suitable support adjacent to one of the eccentric-rods, and a pneumatic tube connecting the said push-button with the said signal, whereby the eccentric-rod in its movement will make direct contact with the push-button, and thereby actuate the signal.

In testimony that I claim the foregoing I have hereunto set my hand, at Milwaukee, in the county of Milwaukee and State of Wisconsin, in the presence of two witnesses.

JAMES C. RICKETSON.
